UNITED STATES PATENT OFFICE.

JAMES E. SLUSSER AND SAMUEL A. STOVER, OF MARSTELLER, PENNSYLVANIA.

AUTOMATIC SWITCH.

Application filed November 8, 1922. Serial No. 599,637.

To all whom it may concern:

Be it known that we, JAMES E. SLUSSER and SAMUEL A. STOVER, citizens of the United States, residing at Marsteller, in the county of Cambria and State of Pennsylvania, have invented certain new and useful Improvements in Automatic Switches, of which the following is a specification.

This invention relates to automatic switches primarily adapted for application to the track-ways employed in mines or stone quarries, whereby the dump cars running over the track-ways will control the actuation of the switch for allowing the cars to run alternately upon the main and side track-way.

In mines or quarries there is generally provided a main and side track-way each provided with a car tipple or storage bin either upon or beneath the track-way and heretofore, it has been necessary to run a car upon the main track-way and then throw a switch for allowing the next car to pass over the side track-way whereby they may be dumped. This procedure occasions a great amount of trouble and necessitates the employment of a switchman for throwing the switch, for controlling the movement of the cars, alternately upon each track-way.

It is therefore the primary object of our invention to provide a switch which at all times will be controlled by the movement of the cars over the main and side track-ways for permitting these cars to alternately pass over the said main and side track-ways.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a plan view of my improved switch, the points thereof being thrown so as to allow the oncoming car to pass onto the side track-way.

Figure 2 is a view similar to Figure 1, but showing the switch points as having been controlled by a car passing over the side track-way for positioning these points so as to allow the next car to run upon the main track.

Figure 3 is an enlarged plan view of the front ends of the switch points, and the connecting means therefor.

Figure 4 is a transverse sectional view upon the line 4—4 of Figure 3.

Figure 5 is a fragmentary elevational view of one of the rails of the track sections showing the train controlled arm positioned adjacent thereto for controlling the movement of the switch points.

Figure 6 is a fragmentary longitudinal sectional view upon the line 6—6 of Figure 1.

Figure 7 is a transverse cross sectional view upon the line 7—7 of Figure 1, and

Figure 8 is a detail perspective view of one of the car actuated arms for the switch points.

With reference to the drawings, and in particular to Figures 1 and 2, we have shown our improved switch as being provided between a main and side track-way A and B respectively. In practicing our invention, we have provided a conventional type of switch frog 5 between the meeting rails of the main and side section, and also having the usual switch points 6 and 7 pivotally secured thereto. As more clearly shown in Figure 4, the switch points 6 and 7 have rigidly secured as at 8 adjacent their outer ends a rod 9, the inner end of which is yoked as at 10 for receiving therebetween a desirable form of turnbuckle 11, whereby these ends of the switch points may be properly adjusted with respect to the adjacent rails of the track sections. The outer ends of each of the rods 9 are similarly yoked as at 12 for pivotally receiving thereon one arm of a bell crank 13, which bell cranks are pivotally secured as at 14 to one of the adjacent ties a.

The other arm of each of the bell cranks 13 are pivotally secured to a link 15 carried by a chain 16, one of which extends parallel with the outer rail of the main track section, and the other of which extends parallel to the outer rail of the side track section as more clearly shown in Figures 1, 2 and 3.

At a point spaced from the switch points 6 and 7 for a distance greater than the length of the dump cars passing over the track sections, the outer rails a' and b' of the main and side track-ways respectively, have pivotally secured adjacent thereto an arm member 17 to be actuated by the wheels of the cars passing thereover as more clearly

shown in Figures 4 to 8. The arms 17 adjacent each of the rails a' and b' are identical in construction, and a description of one will suffice for both. As shown, each of these arms 17 is provided with an enlarged curved head 18 adapted to normally project above the tread of the rails and is keyed or otherwise secured to a rocker arm 19 anchored within a bearing 20, rigidly secured upon one of the ties. The arm members 17 are suitably bored as at 17' for the reception of one end of the rocker shaft 19 and rigidly secured to the opposite end of this shaft 19 is a vertically extending arm or plate 21. It is to be understood further, that the base and tread portions of each of the rails a' and b' are suitably channeled as shown for allowing a free swinging movement of the members 17.

20 The before mentioned chain sections 16 are each connected through the medium of a link 22 with its respective arm 21, adjacent the outer rails of each track section as more clearly shown in Figure 5, and in view 25 of the above description, it will be readily understood that with the switch points 6 and 7 in a position as shown in Figure 1, an oncoming car will be switched to the side track-way B, at which time, the wheels 30 thereof will engage the headed end 18 of the operating member 17 for throwing the switch points 6 and 7 into the position as shown in Figure 2 for allowing the next 35 car to run upon the main track section A and vice versa. It is to be understood that should it be desirable at any time to use only one track section, the device may be disconnected in several different ways, such

for instance, as disconnecting the bell cranks 13 from the switch point carrying rods 9 40 and if found desirable, turn buckles 16' may be provided in each chain section 16 for suitably taking up the slack in these sections.

While we have herein shown and described, the preferred embodiment of the 45 present invention, it is nevertheless to be understood that minor changes may be made therein without departing from the spirit and scope of the invention as claimed.

What we claim as new is:—

1. In automatic switches, a rocking arm pivotally supported adjacent one of the rails of the main and side track-way, the upper end of these rocking arms adapted to extend above the tread of their adjacent rails to be 55 actuated by the wheels of a car passing thereover, and connecting means between each rocking arm and the switch points of the switch for controlling the movement thereof.

2. In an automatic switch, a rocking arm pivotally supported adjacent the outer rail of the main and side section, the upper end of which normally extends above the said rail to be actuated by the wheels of a car 65 passing thereover, rigid connections between the switch points of the switch and chain connections between the switch point connections and the said rocking arms whereby the movement of the switch points are controlled by a car engaging the rocking arm upon either the main or side track-way.

In testimony whereof we affix our signatures.

JAMES E. SLUSSER.
SAMUEL A. STOVER,
